(57) **CLAIM**

The ornamental design for a watering can, as shown and described.

DESCRIPTION

FIG. 1 is a perspective view of a first embodiment of a watering can, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an enlarged partial front view of the section marked 8 in FIG. 2;

FIG. 9 is a perspective view of a second embodiment of a watering can, showing our new design;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof; and,

FIG. 16 is an enlarged partial front view of the section marked 16 in FIG. 10.

The evenly spaced broken lines in the drawings illustrate portions of the watering can which form no part of the claimed design. The dot-dash broken lines illustrate boundaries of the enlarged views and form no part of the claimed design.
